(57) **CLAIM**

I claim the ornamental design for an ISO/DIN auto stereo mounting device with pocket, as shown and described.

DESCRIPTION

FIG. 1 is a right front perspective view of an ISO/DIN auto stereo mounting device with pocket, showing my design;

FIG. 2 is a front elevation view of FIG. 1;

FIG. 3 is a rear elevation view of FIG. 1;

FIG. 4 is a right side elevation view of FIG. 1;

FIG. 5 is a left side elevation view of FIG. 1;

FIG. 6 is a top plan view of FIG. 1; and,

FIG. 7 is a bottom plan view of FIG. 1.

The appearance of my design for an ISO/DIN auto stereo mounting device with pocket, characterized by an ISO/DIN auto stereo mounting space, above a pocket. The mounting structure shown in dotted line forms no part of the claimed design.
